DOOR AND DRAWER ASSEMBLY FOR
COOKING RANGES

Kenneth S. Jenson and Willis N. Nelson, Wisconsin Rapids, Wis., assignors to Prentiss Wabers Products Company, Wisconsin Rapids, Wis., a corporation of Wisconsin

Application May 13, 1950, Serial No. 161,822

7 Claims. (Cl. 126—340)

1

This invention relates to a cooking range and particularly to a door and drawer assembly therefore wherein the drawer mounts a food cooking unit generally designated as a broiler.

In kitchen ranges, especially for use in the home, one of the very desirable features is a broiler. Generally the broiler is located below the baking oven so as to utilize the same heating element for cooking in both compartments. The broiling compartment is equipped with its own door which is normally closed during the cooking operation. It is desirable that the support for food to be broiled in the broiler compartment be shiftable into and out of the compartment to facilitate the placement or removal of food, and to permit inspection thereof during the broiling operation.

The main objects of this invention, therefore, are to provide an improved mounting of a broiler drawer for straight-line sliding movement; to provide an improved connection between the door and the drawer for producing opposite shifting movements of the drawer with opening and closing of the door; to provide improved means for cushioning the drawer at the conclusion of its closing movement, such means also serving to bias opening movements of the door and drawer; to provide an improved door and drawer connection which, in coaction with the cushioning means serves as a toggle to insure holding of the drawer in closed position; and to provide an improved door and drawer assembly in which the connection therebetween is simple in construction, economical to manufacture, and especially suited for use as a broiler unit in a kitchen range.

In the embodiment of our invention shown in the accompanying drawings:

Figure 1 is a fragmentary perspective view of a range whose door and broiler drawer are shown in their open and extended positions, the door and drawer embodying the features of this invention by which swinging of the door produces a concurrent shifting movement of the broiler drawer;

Fig. 2 is a horizontal section, taken on line 2—2 of Fig. 3;

Fig. 3 is a vertical section, taken on line 3—3 of Fig. 2;

Fig. 4 is a similar view in which the door is fully opened and the broiler drawer is shifted outwardly to its extreme forward position; and

Fig. 5 is a fragmentary detail in section, taken on line 5—5 of Fig. 4.

The particular range door and broiler drawer 55 and the back thereof. The

2

assembly herein shown comprises a frame 6 defining inter alia a compartment 7 which is equipped with a door 8. A broiler drawer 9 is slidably supported in the compartment, and shifting of this drawer is responsive to swinging movements of the door 8 by the special motion-transmitting means shortly to be described.

The range frame 6 which may be of conventional construction is mounted on a base 11.

10 Other compartments defined by the frame may be used for cooking and/or storage, and each is equipped with its own door 12. Within the frame 6 and further defining the broiler compartment 7 are arranged a bottom lining 13, side linings 14, and a back lining 15. Rails 16 secured to the bottom lining 13 slidably support the broiler drawer 9, as will more fully be pointed out presently. Plates 17 secured to the sides of the rails 16 intermediate their ends serve as stops to limit 20 outward movement of the drawer 9 and to support the door 8 horizontally in its open position. The door 8 which is of usual construction is hinged at 18 at its bottom to the frame 6 at its front, at a point that is slightly below the plane 15 of the bottom lining 13 for the compartment 7. The door is provided with the usual handle 19.

The broiler drawer 9 may be of any suitable construction. As herein shown, it comprises a pair of plates 20 corrugated to provide a plurality of flat ledges 21, the corrugated plates being secured at their front ends to an interconnecting U-strap 22 and at their rear ends to a back wall 23. Flanges 24 (see Fig. 5) formed along the upper edges of the rails 16 extend inwardly to engage the under side of one of the ledges 21 on each corrugated plate 20 thereby to support the drawer 9 for its sliding movements in the compartment 7.

40 The motion-transmitting connection between the door 8 and the broiler drawer 9 comprises a pair of spaced brackets 25 affixed to the door, and pivoted thereto at 26 a wire bail 27 having its cross piece hinged to clips 28 at the back of the drawer 9. The brackets 25, as herein shown, are

45 each in the form of a right angle triangle with a base flange 29 thereon bonded to the inner face of the door adjacent one of its sides with one of the longer sides of the bracket normal to the face of the door. In the closed position of the door (see Fig. 3), these brackets are disposed above its hinge 18 and also above the compartment bottom lining 13 by a slight distance.

The bail 27 is produced from spring wire which is formed to extend along the sides of the drawer 9 and across the back thereof. The

forward ends of the bail are laterally bent to extend through apertures near the free corners of the two brackets 25 to form pivotal connections therewith at 26. The cross piece of the bail is formed with an angularly disposed V-bend 30 (see Fig. 5) which is arranged to engage the back lining 15 of the compartment 7 as the drawer approaches its fully closed position to cushion its stop at that point. The length of this V-bend 30 is such that its point of contact 31 with the back lining 15 is considerably above the hinge clips 28, and the length of the brackets 25 as well as their disposition on the door 8 is such that, with the door in its closed position, the pivot points 26 15 are below a line 1 extending from the door hinge 18 to the point of contact 31 between the V-bend 30 and the back lining 15. In effect, the bail is a dual link between the door and drawer, acting to transmit a two-way motion therebetween.

The bail 27 and the brackets 25 provide a toggle whose resilient V-bend 30, when engaging the back lining 15, tends to press the pivot points 26 downwardly and maintain the door 8 in its fully closed position. Moreover, by reason of the resiliency of the bail 27, the V-bend tends to urge the door 8 openly and the drawer 9 outwardly when the door is swung outwardly a distance sufficient to raise the pivot points 26 above the line 1.

The bail 27 encloses the stop plates 17 which are engageable thereby to limit the forward movement of the drawer 9, and in so doing it supports the door 8 firmly in its fully open horizontal position (see Fig. 4). Swinging of the door 8 on its hinge 18 transmits motion to the drawer 9 which is thereupon shifted in a straight line that is horizontal and parallel to the bottom lining 13. When the door is open the drawer is readily accessible for the placing, removal, or adjustment of pans or trays 32 (see Fig. 1) on various of the ledges 21 within the broiler compartment 7, as circumstances may require.

We claim:

1. For a cooking range, a door and drawer assembly comprising a frame defining a compartment with an opening, a door hinged at its bottom on the frame to swing about a horizontal axis between a vertical position to close said opening and a horizontal open position, a drawer supported for movement in the compartment in a straight line only, a motion-transmitting connection hinged to the door and to the drawer whereby swinging of the door will produce a sliding movement of the drawer, said motion-transmitting connection comprising resilient means interposed between the back of the drawer and the proximate wall of the compartment to cushion the drawer at the conclusion of its closing movement and bias its opening movement following initial opening of the door, said resilient means and the hinge axis of the motion-transmitting connection with the door being so related that when the door and drawer are in their fully closed positions the hinge axis between the motion-transmitting connection and the door is below a line extending between the hinge axis at the door bottom and the contact point of the resilient means with the compartment wall.

2. For a cooking range, a door and drawer assembly comprising a frame defining a compartment with an opening, a door hinged at

its bottom on the frame to swing between a vertical position to close said opening and a horizontal open position, a drawer supported for movement in the compartment in a straight line only, a bail embracing the sides and back of the drawer and having its ends hinged to the door eccentrically of its hinge axis and its cross piece hinged to the drawer whereby motion is transmitted to the drawer in response to swinging movements of the door, and an angular bend in the cross piece of the bail disposed to contact the proximate compartment wall to cushion the drawer at the conclusion of its closing movement and bias its opening movement following initial opening of the door.

3. For a cooking range, a door and drawer assembly comprising a frame defining a compartment with an opening, a door hinged at its bottom to the frame to swing between a vertical position to close said opening and a horizontal open position, a drawer supported for movement in a straight line only within the compartment, brackets affixed to the door and extending inwardly therefrom along the sides of the drawer, a bail embracing the sides and back of the drawer and having its ends hinged to the inner ends of the brackets and the cross piece of the bail hinged to the back of the drawer adjacent the bottom thereof, the bail cross piece having an angular bend arranged to contact the proximate wall of the compartment and cushion the drawer at the conclusion of its closing movement and bias its opening movement following initial opening of the door.

4. For a cooking range, a door and drawer assembly comprising a frame defining a compartment with an opening, a door hinged at its bottom on the frame to swing between a vertical position to close said opening and a horizontal open position, a drawer supported for sliding movement in the compartment in a straight line only, brackets affixed to the door and extending inwardly therefrom along the sides of the drawer, a bail embracing the sides and back of the drawer and having its ends hinged to the inner ends of the said brackets and the cross piece of the bail hinged to the back of the drawer adjacent the bottom thereof, the cross piece of the bail having an angular bend arranged to contact the proximate compartment wall and cushion the drawer at the conclusion of its closing movement and bias its opening movement following initial opening of the door, the point of contact of the bail bend and compartment wall being such that when the door and drawer are in their fully closed positions the hinge connection of the brackets and bail is below a line extending between the hinge axis of the door and the contact point of the bail bend with the compartment wall.

5. For a cooking range, a door and drawer assembly comprising a frame defining a compartment with an opening, a door hinged at its bottom to the frame to swing between a vertical position to close the opening and a horizontal open position, a drawer having its opposite sides formed with ledges extending longitudinally thereof, rails secured to the frame at the sides of the drawer and flanged along their upper edges to engage the ledges of opposite sides of the drawer and slidably support it for straight line movements only in the compartment, a bail embracing the sides and back of the drawer and having its ends hinged to the door and the cross piece of the bail hinged to the drawer for pivotal

movement about a fixed axis relative thereto whereby to transmit a two-way motion between the drawer and door, and a stop on one of the rails located inwardly of the bail to engage its cross piece for limiting the outward sliding movement of the drawer and supporting the door in a horizontal position, the stop being ineffective for either purpose when the bail is removed from the door and drawer.

6. In a cooking range having a compartment open at the front and closed at the back, a hinged door at the front of the compartment to provide a closure therefor, a drawer within the compartment, means supporting the drawer within the compartment for straight-line movement therewithin, a two-way motion-transmitting connection between the door and drawer comprising a link pivotally connected to the door eccentrically of its hinged axis and pivotally connected to the drawer to move therewith about a fixed axis relative thereto, and means extended rearwardly and upwardly from the link in engagement with the proximate wall at the back of the compartment at a point above the axis of the link connection with the drawer, the link connection with the door being so located as to swing past a straight line extending between the hinge axis of the door and the point of engagement between the means extended from the link and the compartment back wall, shortly before completion of swinging movement of the door to its closed position, and a stop fixedly supported within the compartment and engageable with the link at the conclusion of swinging movement of the door through approximately 90° to a horizontal position to sustain the door at that point.

7. For a cooking range, a door and drawer as-

sembly comprising a frame defining a compartment with an opening, a door hinged on the frame to swing between a vertical position to close said opening and a horizontal open position, a drawer supported for movement in the compartment in a straight line only, a member extending along at least one side of the drawer and having a portion thereof extending along the back of the drawer, said member having its end hinged to the door eccentrically of its hinge axis and said portion of the member being hinged to the drawer whereby motion is transmitted to the drawer in response to swinging movements of the door, and an angular bend in said portion of the member disposed to contact the proximate compartment wall to cushion the drawer at the conclusion of its closing movement and bias its opening movement following initial opening of the door.
